UNITED STATES PATENT OFFICE.

HEINRICH LEISER, OF THORN, GERMANY.

DEVICE FOR MIXING FLUIDS AND MOLTEN METALS OF DIFFERENT DENSITIES.

No. 873,131.

Specification of Letters Patent.

Patented Dec. 10, 1907.

Application filed November 5, 1906. Serial No. 342,091.

To all whom it may concern:

Be it known that I, HEINRICH LEISER, a subject of the Kingdom of Prussia, and a resident of Alter Markt, Thorn, Western 5 Prussia, Germany, have invented certain new and useful Improvements in a Device for Mixing Fluids and Molten Metals of Different Densities, of which the following is a specification.

10 My said invention relates to an improved device for mixing liquids of different density or specific gravity and the object of the invention is to provide an extremely simple, durable and efficient device for quickly and 15 effectively accomplishing such mixing or commingling operation.

The invention includes the special features of construction and arrangement and combination of parts hereinafter described and 20 particularly pointed out in the claims.

An embodiment of the invention is illustrated in the accompanying drawing in which

Figure 1 is a sectional elevation and, Fig. 2 a sectional plan.

25 Referring by reference characters to this drawing D designates a vessel for containing the liquids to be mixed or commingled. A vertical shaft E depends within this receptacle, being journaled in a bearing bracket F and adapted to be rotated by any suitable means such as a pulley G. Secured to this shaft E within the receptacle by means of arms B are a plurality of tubes which have straight inclined portions b held by the tubular clamps A at the ends of the arms. The lower end of each tube is preferably slightly enlarged or flared and curved inwardly and also deflected to one side of a vertical plane 35 passing through the supporting arm as indicated at a in Fig. 2. The opposite upper ends which are brought by the inclination

above referred to, into proximity to the inner periphery of the vessel, are curved or turned in a direction opposite to that of the lower ends as shown at c.

45 In operation the spindle is rotated at a rapid rate of speed in the direction of the arrow. The liquid of greater specific gravity which has settled in the bottom of the vessel is scooped up by or caused to enter the lower 50 ends of the tubes by its inertia. Owing to the outward incline of the tubes centrifugal force then causes it to be carried up the tubes and discharged at the upper end upon the top of the lighter liquid, and this operation 55 is continued until the two liquids are thoroughly commingled.

Having thus described my invention what I claim is:

1. An apparatus for mixing fluids of different specific gravity comprising a receptacle, a vertical shaft depending thereinto with means for rotating it, and an outwardly and upwardly inclined tube supported from said shaft having a forwardly turned lower end. 60

65 2. An apparatus for mixing fluids of different specific gravity comprising a vessel, a vertical shaft depending within the same with means for operating it, arms carried by said shaft, and a tube carried by each arm, each 70 tube having a forwardly turned lower end and a rearwardly turned upper end and an upwardly and outwardly inclined intermediate portion, substantially as described.

75 In witness whereof I have hereunto signed my name this 25th day of October 1906, in the presence of two subscribing witnesses.

HEINRICH LEISER.

Witnesses:

WOLDEMAR HAUPT,
HENRY HASPER.
